HAND-PROPELLED HYDRAULIC LIFTING TRUCK

John H. Klassen, Inman, Kans.

Application December 9, 1949, Serial No. 131,945

2 Claims. (Cl. 254—10)

1

My invention relates to a lifting truck.

A primary object of my invention is to provide a hand-propelled, hydraulic lifting truck, particularly useful for engaging under and lifting low tables or skids heavily loaded with paper, such as used by book publishers and the like.

A further object is to provide a lifting truck of the above-mentioned character which is highly simplified, compact and extremely strong and durable.

A further object is to provide a device of the above-mentioned character including a low, horizontal, hydraulically operated lifting platform which, when in its lowermost position, will engage under a conventional skid or low table only about eight inches high from the floor.

A still further object of the invention is to provide a lifting truck of the above-mentioned character which is very easy to operate, and which should be relatively inexpensive to manufacture.

Other objects and advantages of the invention will be apparent during the course of the following description.

In the accompanying drawings forming a part of this application, and in which like numerals are employed to designate like parts throughout the same:

Figure 1 is a plan view of a lifting truck embodying my invention;

Figure 2 is a side elevation of the same;

Figure 3 is a central, vertical, longitudinal section taken on line 3—3 of Figure 1;

Figure 4 is a transverse, vertical section taken on line 4—4 of Figure 3;

Figure 5 is a similar section taken on line 5—5 of Figure 3; and

Figure 6 is a transverse, vertical section taken on line 6—6 of Figure 3, parts omitted.

In the drawings, where, for the purpose of illustration, is shown a preferred embodiment of my invention, the numeral 10 designates generally a horizontal support frame of welded construction. This support frame 10 comprises a pair of transversely spaced, longitudinal, outer bars or sides 11, which are straight throughout the major portion of their length, and bent near their forward ends to form forwardly converging sections 12, in turn bent at their forward ends to form opposed, laterally spaced, short longitudinal extensions 13. The rear ends of the sides or bars 11 are rigidly secured together by a transverse end bar 14 having its opposite ends welded to the adjacent ends of the bars 11. A pair of inner, longitudinal, horizontal bars or rails 15 have one

2

pair of ends rigidly secured to the transverse bar 14 by welding, and the opposite ends of the bars 15 are rigidly secured to the forward ends of the converging portions or sections 12 by welding. The inner bars 15 are spaced laterally inwardly from the outer bars 11, as shown, and the bars 11 and 15 are parallel. The inner bars 15 are in longitudinal alignment with the extensions 13. Arranged near the longitudinal centers of the inner bars 15 and extending transversely between such bars is a transverse brace or bar 16 having its opposite ends welded to the bars 15. The elements thus far described constitute a unitary, low, rigid, horizontal frame 10 which is generally rectangular and elongated, as shown in Figure 1.

A transverse, horizontal shaft or axle 17 is arranged near and inwardly of the transverse end bar 14, and is rigidly secured within aligned openings in the bars 11 and 15. The axle 17 extends for the entire distance between the outer bars 11. Rotatably mounted upon the axle 17 between the pairs of bars 11 and 15 are pairs of wheels or rollers 18 which may be formed of hard rubber or steel. The wheels 18 are of such diameter that they support the adjacent end of the horizontal frame 10, preferably approximately two inches above the floor.

A body or casing 19 is rigidly secured by welding to the sections 12 and extensions 13 of the support frame. The bottom of the casing 19 is open, and the casing projects above the support frame 10, as shown. The body or casing 19 includes an outer, relatively narrow end portion 20 having a vertically disposed, rounded end 21 extending longitudinally forwardly of the extensions 13, as shown. The opposite vertical sides of the relatively narrow body portion 20 are arranged between the extensions 13 and secured thereto by welding. The body 19 further includes an inner, relatively wide portion 22 having a horizontal, flat top or step 23 arranged at an elevation above the flat top 24 of the relatively narrow body portion 20. The opposite sides of the body portion 22 are vertically disposed and converging, and arranged between the converging sections 12 and rigidly secured thereto by welding. The body or casing 19 includes an inner, vertical end 25 extending from the top 23 to the top of the support frame 10. The bottom edge of the body or casing 19 is flush with the bottom of the support frame 10, as shown. A narrow, vertical panel or riser 26 extends transversely across the body 19 at the forward end of the relatively wide portion 22 and connects the tops

23 and 24, being secured thereto by welding. The body or casing 19 forms with the support frame 10 a unitary rigid structure. A caster 27 has its top end pivotally secured to the under side of the top 24, and the caster is arranged within the relatively narrow body portion 20, as shown, and includes a caster wheel 28 which projects below the bottom of the body 19 and supports the body and adjacent end of the support frame 10 approximately two inches above the floor. The 10 caster wheel 28 is preferably slightly larger in diameter than wheels 18. The caster 27 is disposed at the transverse center of the truck and equidistantly between the pairs of wheels 18.

Rigidly secured by welding to the panel 26 and top 24 at opposite ends of the panel 26 are vertical webs or corner plates 29 having aligned apertures rotatably receiving bottom, opposed, transverse extensions 30 of elongated, straight, parallel, transversely spaced bars 31 of a truck guide handle 32. Rigidly secured to the tops of the bars 31 are opposed, laterally outwardly projecting extensions or handlebars 33, preferably formed integrally with the bars 31, as shown. The bars 31 are disposed near and upon opposite sides of the longitudinal center line of the truck, and are laterally spaced apart, as shown. The bars 31 are rigidly connected near their top ends by a transverse brace plate 34 welded to the bars, and a similar transverse brace plate 35 is rigidly secured between the bars 31 by welding near the longitudinal centers of the bars. Near and above the lower ends of the bars 31, a pair of closely spaced locking plates 36 are arranged between the bars and secured thereto by welding. All of the plates 34, 35 and 36 have aligned openings midway between the bars 31 slidably receiving an elongated locking bar or bolt 37 having a handle 38 above the plate 34. The bottom end of the locking rod or bolt 37 extends between the locking plates 36 and engages in any one of longitudinally spaced openings 39 of a handle adjusting segment or bar 40, pivotally connected at its bottom end, as shown at 41, with the top 24 of the body. The handle adjusting segment 40 is arcuate, as shown, and arranged at the transverse center of the truck and midway between the bars 31, so that the handle 32 may be adjusted to the desired inclination by engaging the bolt 37 in various ones of the openings 39. The handle 32 serves as means for pushing or pulling the truck, and steering the same upon the caster 27.

An expansible coil spring 42 surrounds the bolt 37 between the plate 35 and the uppermost plate 36. The top end of the spring 42 engages the plate 35 and its bottom end is connected with the bolt 37, and resiliently urges the bolt downwardly for engagement within the apertures of the plates 36 and member 40.

A vertically adjustable, flat horizontal, rectangular platform 43 is provided, and this platform is arranged above and completely covers the portion of the support frame 10 beyond the body 19. The platform 43 includes a flat, rectangular top 44 and opposed, depending, vertical side and end flanges or plates 45 and 46. The platform 43 may also be of welded construction. When the platform is in the lowered position, the side flanges 45 engage upon the outer longitudinal rails 11 of the frame 10, and the outermost end flange 46 engages upon the transverse bar 14 of the support frame. Near and inwardly of its opposite ends, the platform 43 is provided close to and below its top 44 with transverse, horizontal, ro-

tatable shafts or hinge pins 47 and 48 journaled upon the side flanges 45. Rigidly secured by welding to the hinge pins 47 and 48 adjacent to the opposite ends of the same are flat, rectangular, depending hinge plates or lifting arms 49 which extend downwardly between the pairs of rails 11 and 15, and are rigidly secured therebetween by welding to relatively short, horizontal, rotatable, lower shafts or hinge pins 50 journaled upon the pairs of rails 11 and 15, as shown. The four plates or lifting arms 49 thus carry the platform 43 bodily, and the lifting arms 49 are swingable vertically to raise and lower the platform 43, maintaining it horizontal at all times. Stop blocks 51 are rigidly secured by welding to the outer faces of the inner rails 15, and these stop blocks are arranged above the hinge pins 50, Figure 3, for engaging the lifting arms or plates 49 when such arms are in substantially vertical positions to limit the upward travel of the platform 43. A strong, retractile coil spring 52 is provided for biasing the platform 43 in the lowermost position. This spring 52 extends longitudinally of the truck and is arranged at its transverse center. The rear end of the spring is connected with an apertured lug 53 rigidly secured to the adjacent transverse flange 46 of the platform by welding. The opposite end of the spring 52 is detachably connected with a hook 54 rigidly secured to the transverse bar or brace 16 at the longitudinal center of such brace.

For raising and lowering the platform 43, I provide a hydraulic jack 55 of conventional construction, and including a body portion or cylinder 56 extending longitudinally of the truck and arranged at an inclination to the horizontal, as shown. The cylinder 56 is disposed at the transverse center of the truck and platform 43, and longitudinally slidably mounted within the cylinder is the usual ram or piston rod 57 pivotally connected at 58 with an apertured lug or bracket 59 welded to the adjacent end flange 46 of the platform at the transverse center of the platform. An opening 60 is provided in the end or panel 25 for the ram 57 to operate through, Figure 3. Rigidly secured to the lower end of the cylinder 56, and preferably formed integrally therewith, is a transverse base plate 61 having its bottom rigidly secured by welding to a transverse, horizontal hinge pin or shaft 62 journaled at its opposite ends in sleeves or bearings 63 formed upon opposed, longitudinal, horizontal plates 64, in turn rigidly mounted upon the adjacent inner faces of the extensions 13 and rails 15.

Adjacent to one side of the jack cylinder 56 and rigidly mounted upon the base plate 61 thereof and extending above the base plate 61 is the usual jack pump or actuator 65 including a reciprocating plunger rod 66 operatively connected with an upstanding operating lever 67 pivotally connected with the plunger rod 66 of the pump, as at 68. The lower end of the operating lever 67 extends below the pump 65 and is pivotally connected, as at 69, with a short link 70 pivotally connected at its lower end with an apertured lug 71 formed upon the base plate 61. The operating lever 67 extends upwardly through the portion 22 of the body 19 and through a longitudinal slot 72 formed in the top 23. The lever 67 is swingable longitudinally in a vertical plane for actuating the pump plunger rod 66 for extending the ram 57 of the jack to raise the platform 43. The hydraulic jack 55 further includes an exhaust or control valve 73 having

a transverse stem 14 which extends through the adjacent frame section 12 and outwardly of the side of the truck adjacent to the exhaust valve 13, Figure 1. The stem 14 has a handle or knob 15 operable to exhaust the fluid under pressure from the bottom of the cylinder 56 so that the spring 52 may return the elevated platform 43 to its lowermost position.

In use, the handle 32 may be adjusted at the desired inclination, as previously described. This handle is used for pulling or pushing the truck and steering the same upon the caster 21. With the platform 43 in its lowermost position and resting upon the top of the support frame 10, the end of the truck having the platform may be rolled beneath a skid loaded with papers or the like to be lifted. The lever 67 is then swung forwardly and rearwardly to actuate the plunger of the jack pump 65 for extending the ram 57 outwardly of the cylinder 56 to the desired amount. The ram 56 will thus elevate the platform 43 the desired amount for lifting the skid from the floor. The upward movement of the platform 43 is limited by the stop blocks 51 which contact the plates or arms 49 when they are substantially vertical. When the loaded skid has been transferred to the desired point, it is merely necessary to turn the knob 75 of the exhaust valve 13 and thus release the pressure within the cylinder 56 of the jack so that the spring 52 may return the platform 43 to the lowered position where it rests upon the support frame 10. When this has been done, the skid will, of course, be returned to the floor. The truck is highly simplified in construction, very compact, extremely strong and easy to operate.

It is to be understood that the form of my invention herewith shown and described is to be taken as a preferred example of the same, and that various changes in shape, size and arrangement of parts may be resorted to without departing from the spirit of my invention or the scope of the subjoined claims.

Having thus described my invention, I claim:

1. A lifting truck, comprising a low elongated horizontal support frame, wheels mounted upon one end of the support frame for supporting such end, and upstanding casing secured to the opposite end of the support frame and having its bottom open and projecting above the support frame, a steering caster mounted within the casing and connected with the top of the casing and including a wheel projecting below the casing for supporting the casing and the adjacent end of the support frame, a truck propelling and steering handle connected with the top of the casing and projecting above the casing for a substantial distance, a vertically shiftable lifting platform for the truck and arranged above the frame beyond the casing, vertically swingable hinges connecting the platform and frame, stops secured to the frame for engaging the hinges to limit their upward swinging movement, a spring connecting the platform and frame and serving to bias the platform toward a lowermost position, a hydraulic lifting jack mounted within the casing and having one end pivotally connected with the frame, the jack including a ram having its outer end pivotally connected with one end of the platform to raise and lower the platform, the

casing including an end provided with an opening, the ram operating through said opening when actuated to raise and lower the platform, an upstanding vertically swingable ram operating lever pivotally connected near its lower end with the jack, the top of the casing having a slot formed therein, the upstanding ram actuating lever extending through the slot and above the top of the casing for a substantial distance, the ram actuating lever being arranged near the handle of the truck, and being swingable for extending the ram to raise the platform of the truck, and an exhaust valve for the lifting jack and operable to relieve the pressure behind the ram so that the spring may shift the lifting platform to its lowermost position.

2. A lifting truck comprising a low elongated horizontal support frame, wheels mounted upon one end of the support frame for supporting such end, and upstanding casing secured to the opposite end of the support frame and having its bottom open and projecting above the support frame, a steering caster mounted within the casing and connected with the top of the casing and including a wheel projecting below the casing for supporting the casing and the adjacent end of the support frame, a truck propelling and steering handle connected with the top of the casing and projecting above the casing for a substantial distance, a vertically shiftable lifting platform for the truck arranged above the frame beyond the casing, means for connecting the platform and frame for upward swinging movement, stops secured to the frame for engaging the said means to limit said upward swinging movement, a spring connecting the platform and frame and serving to bias the platform toward a lowermost position, a hydraulic lifting jack mounted within the casing and having one end pivotally connected with the frame, the jack including a ram having its outer end pivotally connected with one end of the platform to raise and lower the platform, the casing including an end provided with an opening, the ram operating through said opening when actuated to raise and lower the platform, an upstanding vertically swingable ram operating lever pivotally connected near its lower end with the jack, the ram actuating lever being arranged near the handle of the truck, and being swingable for extending the ram to raise the platform of the truck, and an exhaust valve for the lifting jack and operable to relieve the pressure behind the ram so that the spring may shift the lifting platform to its lowermost position.

JOHN H. KLASSEN.
